UNITED STATES PATENT OFFICE.

WALTER A. WESTBROOK, OF KINGMAN, KANSAS.

WAGON-BRAKE LEVER.

SPECIFICATION forming part of Letters Patent No. 378,123, dated February 21, 1888.

Application filed October 8, 1887. Serial No. 251,810. (No model.)

To all whom it may concern:

Be it known that I, WALTER A. WESTBROOK, a citizen of the United States, residing at Kingman, in the county of Kingman and State of 5 Kansas, have invented certain new and useful Improvements in Wagon-Brakes; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

The special object of the invention is to remove certain objections which exist against 15 the wagon-brake lever described in Patent No. 232,363 and analogous brake-levers.

My improvements will first be described in connection with the drawings, and then pointed 20 out in the claims.

Figure 1 of the drawings is a side elevation; Fig. 2, a longitudinal vertical section on the dotted line $x-x$ of Fig. 1, and Fig. 3 a transverse vertical section on the dotted line $y-y$ of 25 Fig. 1.

In the drawings, A represents an internally-toothed arc bar or rack in which works the traveling pinion B, that turns on a cross-pivot, C, in the slot d of the brake-lever D, and F the 30 grip-lever. A' A' are braces. All these devices are old and well known.

At right angles to and crossing the slot d is a slot, d' , in which works up and down the hook E, whose shank is pivoted at the upper end to 35 the grip-lever F, which turns on a pivot, f, in the slot d' . By grasping with the hand the two levers D F and pressing them together the hook E is forced out of the pinion B, and the latter thereby unlocked from the rack, so as to allow 40 the lever to be moved in either direction to apply or remove the brake-shoes from the wheels.

G is the pivoted connection which operates the brake-shoe mechanism.

On the lever D and in front of the lever F, I

place the plate-spring H, fastened at one end 45 on the upper end of said lever D and passing with its other end loosely through the brake-lever slot d' against the grip-lever shoulder f'. By this arrangement of the spring H the brake-strain is no longer upon it, but only that of the 50 hand-grip. This renders it much more durable and much less liable to get out of order.

In practice the studs and cogged stops which are usually employed to lock the pinion B to the rack A are very apt to break off, while my 55 hook E, which is made of metal, is not, while it also operates more perfectly and more promptly.

I am aware that the rack and pinion have been long used in brake-levers, and that studs 60 or cogs have been employed to lock the pinion; but they are in separate pieces pivoted to the lower end of the grip-lever connecting-rod. In practice these pivoted studs or cogs are liable to cramp, so that the brake will not 65 work freely, and also to come off the end of the connecting-rod; hence I use as a stop the hook E, made integral with the connecting-rod, which entirely overcomes the objections 70 to the separate pivoted studs or cogs.

What I claim as new, and desire to protect by Letters Patent, is—

1. In brake-levers, the grip-lever connecting-rod provided with an end hook, E, adapted to be used in connection with the pinion, as 75 shown and described.

2. In brake-levers, the combination of the main lever D, having the slot d , the grip-lever F, pivoted in said slot and having shoulder f', and the flat grip-lever spring H, passing through 80 slot d , as shown and described.

In testimony whereof I affix my signature in presence of two witnesses.

WALTER A. WESTBROOK.
